CLAIM

(62) Division of application No. 35/512,766, filed on Apr.
22, 2021 (U.S. filing date under 35 U.S.C. 384), and
having an international filing date of Apr. 22, 2021,
now Pat. No. Des. 962,883.

The ornamental design for a temporary protective film for
manufacturing semiconductor devices, as shown and
described.

(30) **Foreign Application Priority Data**

DESCRIPTION

Nov. 2, 2020 (JP) ..... 2020-023694 D
Nov. 2, 2020 (JP) ..... 2020-023695 D

FIG. 1 is a front, top and left side perspective view of a
temporary protective film for manufacturing semiconductor
devices of the present invention;

(51) **LOC (14) Cl.** 13-99

FIG. 2 is a rear, bottom and left side perspective view of the
thereof.

(52) **U.S. Cl.**

FIG. 3 is a front, top and right side perspective view of the
thereof.

USPC D13/199

FIG. 4 is a front view of the thereof.

(58) **Field of Classification Search**

FIG. 5 is a rear view of the thereof.

USPC D13/199; D19/72, 99, 69, 67; D7/619.1;

FIG. 6 is a top view of the thereof.

D24/189

FIG. 7 is a bottom view of the thereof.

CPC H01L 21/67132; H01L 23/295; B65H

FIG. 8 is a left side view of the thereof.

(Continued)

FIG. 9 is a right side view of the thereof; and, FIG. 10 is a sectional view taken along the line 10-10 of FIG. 8.

1 Claim, 10 Drawing Sheets
